UNITED STATES PATENT OFFICE

2,024,540

SMOKING PIPE

Milton Schnaier, New York, N. Y.

Application May 21, 1934, Serial No. 726,680

5 Claims. (Cl. 131—12)

My invention relates to improvements in smoking pipes, and the same has for its object to provide a pipe of the inverted type which is simple in construction, efficient in operation, and comparatively inexpensive to produce.

Further, said invention has for its object to provide a pipe in which the oil and distillates released or produced in the course of smoking will be diverted into a collecting receptacle before they can reach the mouth piece of the pipe.

Further, said invention has for its object to provide a pipe which may be readily separated into its component parts to facilitate cleaning thereof.

Further, said invention has for its object to provide a pipe including an inverted bowl, and a top member detachable from said bowl whose interior forms a comparatively large receptacle or chamber between the bowl and the top member for initially receiving the smoke.

Further, said invention has for its object to provide a pipe in which the bowl has a top member detachably secured thereto, and the latter provided with a recessed portion forming a smoke chamber, and a depending tubular portion having a collecting receptacle at its free end, and an angular shank intermediate its ends to receive one end of a mouth piece or bit.

Other objects will in part be obvious and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawing—

Figure 1 is a side view showing one form of pipe constructed according to, and embodying my said invention;

Fig. 2 is a bottom view thereof, and

Fig. 3 is an enlarged central section on the line 3—3 of Fig. 2.

In said drawing 10 designates the bowl of the pipe which is substantially cylindrical in form and provided with a central opening or passage 11 extending the full length of the bowl. The bowl is provided at its upper end with an annular recess 12 into which is rigidly fitted an interiorly threaded metal sleeve 13 whose upper edge is flush with the upper edge of the bowl 10.

14 denotes the top comprising a circular portion 15 which corresponds in outline substantially with the upper end of the bowl 10, and has 55 a circular recess 16, constituting a smoke cham-

ber, in its underside corresponding substantially to the passage 11 in the bowl 10. The underside of said circular portion 15 is provided with an annular recess into which is fitted a metal sleeve 17 having its lower portion, which projects outwardly from the circular portion 15, provided with screw threads adapted to engage with the interiorly threaded portion of the sleeve 13 of the bowl 10 to hold said parts duly united.

From one side of the circular portion 15 extends outwardly and downwardly a tubular portion 18 having a passage 19 therein communicating at its inner end centrally with the recess or smoke chamber 16. The outer, free end of said tubular portion 18 is provided with a reduced 15 end to receive a cap 19a whose interior, together with the enlarged recessed portion of the tubular portion 18, forms a collecting receptacle 19b in which is disposed a mass of cotton, or other suitable absorbent material 20.

20 The tubular portion 18 is provided intermediate its ends with a laterally extending shank 21 having a bore 22 therein communicating with the passage 19 in the tubular portion 18. The said bore 22 is enlarged at the outer end of said 25 shank to receive the reduced end 23 of the mouthpiece or bit 24.

Between the upper end of the bowl 10 and the lower end of the sleeve 17 of the top 14 is clamped a removable, dished strainer 25 which serves to 30 maintain the tobacco in the bowl 10 separated from the smoke chamber 16.

The lower, open end of the bowl 10 is provided at one side with an enlargement or projection 26 to receive one end of a shouldered screw 35 27 which extends through a perforated cover 28, and serves to hold the same rotatably secured to the bowl, and at its opposite side the bowl is provided with a pin 29 having a rounded head 30 adapted to be received by and frictionally engaged with a registering recess in the inner side 40 of the perforated cover 28 to hold the cover locked to closed position.

The operation of the pipe will be largely obvious from the foregoing description. It is to be 45 observed, however, that in filling the bowl with tobacco, the pipe should be inverted, i. e., the bottom of the bowl uppermost, and after the tobacco has been inserted therein and lighted, the cover 28 is closed. The pipe may then be 50 held in the position illustrated at Figs. 1 and 3, and the smoke drawn upwardly into the smoke chamber 16, and thence through the tubular portion 18, shank 21, and mouth piece 24. Any oils, distillates or condensates released or produced 55

by the burning of the tobacco will be carried off through the smoke receptacle 16 and tubular portion 18, and be absorbed by the cotton or absorbent material 20 in the receptacle 19^a, and 5 allow the substantially dry smoke to be drawn through the shank 21 and mouth piece 24.

It is to be noted that the relatively large smoke receptacle 16 acts to receive the produced smoke in the first instance, and thereby serves to insure 10 the passage of some air through the mass of tobacco in the bowl, and the continued burning of the tobacco upwardly within the bowl.

Having thus described my said invention, what I claim and desire to secure by Letters Patent is:

15 1. A smoking pipe comprising a bowl having open upper and lower ends, a cover for said open lower end, a top member detachably secured to the open upper end of said bowl, an annular shoulder in the open, upper end of said bowl, a strainer supported on said shoulder, a tubular portion formed integrally with said top member and extending downwardly and outwardly therefrom, a collecting receptacle detachably secured to the lower end of said tubular portion, and a 20 tubular shank extending outwardly from said tubular portion.

2. A smoking pipe comprising a bowl having open upper and lower ends, a cover for said open lower end, a top member detachably secured to the open upper end of said bowl, an annular shoulder in the open, upper end of said bowl, a strainer supported on said shoulder, a tubular portion formed integrally with said top member and extending downwardly and outwardly therefrom, a collecting receptacle detachably secured to the lower end of said tubular portion, and a tubular shank located intermediate the ends of said tubular portion and extending outwardly therefrom.

30 3. A smoking pipe comprising a bowl having open upper and lower ends, a cover for said open lower end, a top member detachably secured to the open upper end of said bowl having a recess therein registering with the interior of said bowl 35 and forming a smoke receptacle, a strainer in the

upper end of said bowl separating the interior of said bowl from said smoke receptacle, a tubular portion extending downwardly and outwardly from said top member, a collecting receptacle detachably secured to the lower end 5 of said tubular portion, a tubular shank extending angularly from said tubular portion and a mouth-piece extending from said tubular shank.

4. A smoking pipe comprising a bowl having open upper and lower ends, a cover for said open lower end, a top member, a strainer disposed between said bowl and said top member serving to separate the same into two compartments arranged partly in said bowl and partly in said top member for detachably securing said parts together, a tubular portion formed integrally with said top member and extending downwardly and outwardly therefrom, a collecting receptacle detachably secured to the lower end of said tubular portion, and a tubular shank extending outwardly from said tubular portion.

5. A smoking pipe comprising a bowl open at its upper and lower ends, a perforated cover pivotally secured to said bowl for closing said lower end, a screw threaded sleeve secured in the open, upper end of said bowl, a top member including a circular portion conforming to the upper end of said bowl, a recess therein forming a smoke chamber, a threaded sleeve secured in 30 said recess engaging with the threaded sleeve of said bowl for securing said parts in assembled relation, a separate strainer disposed in the open, upper end of said bowl and maintained in place by said top member, a tubular member formed 35 integrally with the circular portion of said top member and extending downwardly and outwardly therefrom, a collecting receptacle detachably secured to the free end of said tubular member, a shank extending laterally outward 40 from said tubular member at a point intermediate the ends of said tubular member, and a mouth-piece secured to the end of said shank.
